INTERNAL-COMBUSTION ENGINE.

1,131,436.

Specification of Letters Patent.

Patented Mar. 9, 1915.

Application filed August 22, 1913. Serial No. 786,069.

To all whom it may concern:

Be it known that we, CHARLES L. SNYDER and FRED J. PEASE, citizens of the United States, residing at Stratford and Bridgeport, respectively, in the county of Fairfield and State of Connecticut, have invented certain new and useful Improvements in Internal-Combustion Engines, of which the following is a full, clear, and exact description, such as will enable other skilled in the art to which it appertains to make and use the same.

This invention relates to methods of converting the potential energy of liquid fuels into power, and to engines for converting such energy, and with respect to its more specific features the invention relates to the method of converting the energy of liquid hydrocarbon oil fuels into power, and to internal combustion engines of the four cycle type designed to carry out the method referred to.

One of the objects of the invention is the provision of a practical method for converting into power the energy potential in liquid hydrocarbon and so as to effectively utilize a larger proportion of heat units than has heretofore been attained.

Another object of the invention is to provide an internal combustion engine utilizing relatively heavy liquid fuel and which may be readily started without the necessity for artificially heating the fuel.

Another object of the invention is to provide a practical engine of the character described adapted to use relatively heavy liquid hydrocarbon fuel, such as kerosene, crude oil, etc., and to avoid the expenditure of energy otherwise consumed in heating such fuels prior to their entry into the cylinder.

Another object of the invention is the provision of an efficient engine of the character described, of increased power and fuel economy over other engines.

Other objects will be in part obvious and in part pointed out hereinafter.

The invention accordingly consists in the several steps and the relation and order of one or more of such steps with relation to each of the others thereof, and in the features of construction, combinations of ele-

ments and arrangement of parts, which will be exemplified in the method hereinafter disclosed and the construction hereinafter set forth, and the scope of the application of each of which will be indicated in the following claims.

In the accompanying drawings, illustrating one embodiment of the invention, and wherein similar reference characters refer to similar parts throughout the several views,—Figure 1 represents a side view of an engine and its appurtenances, partly in section; and Figs. 2 and 3 are sectional views of detailed portions of the engine, mainly diagrammatic, in order to more clearly disclose the construction and operation.

Referring now more particularly to the drawings, the numeral 1 indicates a cylinder of an internal combustion engine having the customary water jacket 2.

The numeral 3 indicates the crank shaft of the engine, 4 the crank, and 5 the piston rod.

The numeral 6 indicates the cam shaft having cams 7 and 8 disposed, respectively, opposite valve rods 9 and 10, which latter are mounted in suitable guides on the side of the cylinder, and at their upper ends are provided with valves 11 and 12, the former controlling an air inlet port, or opening, 13 leading into the cylinder, and the latter an exhaust opening 14 through which the products of combustion are ejected from the cylinder, whence they are conducted away through a suitable pipe 14'.

15 indicates a carbureter, which may be of any approved type, depending in a measure upon the character of oil employed and the manner of its introduction into the engine cylinders, but preferably said carbureter is a suction carbureter provided with an air inlet passage 15' into which the fuel nozzles discharge and through which air passes and on its passage entrains oil in the usual manner.

17 indicates a pipe connecting the carbureter with the engine cylinder and through which the atomized oil and air from the carbureter pass to said cylinder, and 18 is a check valve adapted to be opened by suction when the force of suction is sufficient, in order that the carbureted air may be

drawn into the engine cylinder, this valve preventing retrogression of the fluid mixture toward the carburetor.

19 represents a lever operatively connected to the ignition apparatus, for advancing the spark.

A throttle valve 20 is placed in pipe 17, and provided with a suitable operating device.

18 The cam shaft 6 is driven from the crank shaft 3 through the instrumentality of gears 21 and 22 of such size as to properly time the cam shaft 6, as is usual in engines of this type. Suitable usual auxiliary devices are employed in connection with the engine, such as an electric sparking device timed to ignite the mixture in the cylinder at proper intervals, and a clutch device whereby the crank shaft of the engine may be thrown into operative connection with the element to be driven by the engine. It may be noted at this point that, on account of the facility with which this engine is started under heavy oil, the engine is well adapted for automobiles, as well as stationary and marine work.

The valves 9 and 10 are adapted to be positively lifted by the cams 7 and 8 and the ports controlled thereby opened, and said valves are returned to their seats by the springs 23 and 24, respectively. As before stated, the valve 11 controls an air inlet opening 13. Said opening 13 communicates with the atmosphere through a short pipe or member 25, so that when the valve 11 is open air may freely enter the cylinder, its entrance being augmented by the suction stroke of the piston of the engine. The area of the atmospheric air inlet passage is so proportioned relatively to the area of the passage for the admission of carbureted air that when the valve 11 is open, and the piston is descending upon its suction stroke, only air from the atmosphere will enter, the opening 13 being so relatively larger than the opening controlled by the valve 18 that the latter valve will remain seated as long as the valve 11 is open. When the valve 11 is closed, however, the force of suction through the carburetor and valve 18 will be increased sufficiently to cause the valve 18 to move downwardly against its spring, whereupon carbureted air will be drawn into the cylinder upon the suction stroke, and at a greater rate of speed than the air through said inlet.

While the present invention is capable of being utilized with the lighter hydrocarbon fuels, such as gasoline, naphtha, etc., it is particularly adapted for the utilization of the heavier hydrocarbon fuels, such as kerosene, crude oil, etc., and these latter heavier hydrocarbons may be employed both in starting and in running without the preliminary heating or vaporizing of said oils,

which has heretofore been thought to be necessary when the heavier oils were employed. In running an internal combustion engine under heavy oil, such as kerosene, an ordinary practice is to conduct the liquid fuel mixed with air through a pipe heated so as to practically vaporize the oil fuel before its entry into the engine cylinder. This has ordinarily been accomplished by leading the exhaust from the engine around the conduit for the oil between the carburetor and the engine cylinder. In said prior practice it is evident that, on account of the increased volume of the vaporized oil, a less number of heat units per stroke enters the cylinder, and furthermore that some energy of the engine is necessarily consumed in driving the exhaust in the passageways so as to heat the incoming oil. The present invention avoids the losses of efficiency attendant upon said prior practices, and the result is a practical engine which will utilize kerosene and similar liquid fuels with increased efficiency, and by means of a less complicated apparatus, all of which makes for economy both in construction and in consumption of fuel.

In the present embodiment the cam 7, which controls the air inlet valve 11 is so set and timed as to open the valve 11 immediately at the beginning or just prior to the beginning of the inlet, or suction stroke of the piston. As the piston moves downwardly upon its suction stroke, pure air or air from the atmosphere, at normal temperature, will enter the cylinder through the port 13 and fill the gradually expanding volume of the cylinder. At a point prior to the completion of the suction stroke the atmospheric air inlet valve 11 is closed by its spring 23, the cam 7 being then so positioned as to permit such closure. While the point of the suction stroke at which the valve 11 is closed may be varied within reasonable limits, it has been found in practice that a closure of the valve 11 at three-quarters of the suction stroke accomplishes very efficient results. After the valve 11 has been closed, the valve 18 will automatically open under the influence of the suction, as will be understood from what has been hereinbefore stated, and the atomized mixture of air and relatively heavy liquid hydrocarbon will be drawn into the cylinder for the remaining quarter part of the suction stroke. The atomized fuel mixture will become distributed in the air previously drawn into the cylinder, and upon the succeeding upward stroke of the piston the mixture of air and fuel will be compressed in the usual manner into a relatively small space at the top of the cylinder adjacent the valve 18, which latter, of course, will be closed upon the increase of pressure due to compression.

At the proper time, either just before or immediately after the upper dead center is reached, the igniter will be operated and the mixture exploded, whereupon the piston descends upon its power stroke to be followed by the upward exhaust stroke, as usual in engines of the four-cycle type, the cam 8 opening valve 12 at the beginning of the exhaust stroke. As soon as the exhaust stroke has been completed and the piston begins to descend upon its next suction stroke, the valve 11 will be positively opened as before, and the cycle of operations just described will be repeated.

It will be noted that neither the air nor the fuel oil are artificially heated. Each is drawn from a supply which is at normal temperature; that is, such temperature as the air or oil might ordinarily have under ordinary atmospheric conditions, without designed artificial heating means. The pure "cold" air from the atmosphere is sucked into the engine cylinder for the larger part of the inlet stroke, and the "cold" oil is drawn in for a smaller fraction of the stroke, which latter fraction may be readily regulated by relatively adjusting the cam 7 on the cam shaft 6, as may be desired. The cam 7 will positively open the atmospheric air inlet valve 11 at the beginning of the suction stroke, and when said valve closes, the force of suction through the carburetor will be increased and the air entering the independent air inlet opening in the carburetor will become mixed with the oil and drawn into the cylinder through check valve 13. As the oil is not injected into the cylinder until its expanding volume is filled with pure, relatively cool air from the atmosphere, the oil enters a relatively cool cylinder in which the air is substantially pure. Furthermore, the oil enters a cylinder in which the pressure is slightly below atmospheric, being the further amount of oil. The piston is caused to descend so that the volume of the cylinder is increased, the pressure of oil being so balanced as to expand under the reduced pressure, and they are then in a state of explosive equilibrium to subsequently mix with the cylinder air. The oil is then positively injected upon just a definite portion of the stroke, thus affording a chance of fuel entering until the oil is used in the stroke is attained at which point it is desired. By the time the oil enters the cylinder has been cooled, and to render certain minute projections of the cylinder bore are also here cooled to such an extent as to obviate all danger of accidental pre-ignition. The exhaust pipe leads from the cylinder and is generally spaced from the fuel mixture, and so as not to transmit heat to the entering fuel mixture, this latter being thus maintained in a relatively dense condition and a greater weight of oil entering the cylinder per stroke.

It would be the case if said mixture were heated in its passage to the cylinder. Thus, to the novel described construction is an application among others the objects hereinbefore stated.

Various changes could be made in carrying out the above method, and in the above construction, and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention which, as a matter of language, might be said to fall therebetween.

Having described our invention, what we claim as new and desire to secure by Letters Patent is:

1. The method of obtaining power from liquid hydrocarbon, which comprises introducing a mixture of air and relatively heavy liquid hydrocarbon at normal temperature into an expandable chamber filled with air, compressing the resultant mixture, igniting the compressed mixture, and allowing the ignited mixture to expand.

2. The method of obtaining power from liquid hydrocarbon, which comprises introducing an atomized mixture of air and relatively heavy liquid hydrocarbon at normal temperature into an expandable chamber filled with air, compressing the mixture so formed, igniting the compressed mixture, and allowing the ignited mixture to expand.

3. The method of obtaining power from liquid hydrocarbon, which comprises introducing an atomized mixture of air and relatively heavy liquid hydrocarbon at normal temperature into an expandable chamber filled with air, removing it in an air supply at normal temperature, compressing the mixture so formed, igniting the compressed mixture, and allowing the ignited mixture to expand.

4. The method of obtaining power from an internal combustion engine which comprises introducing air into the cylinder for a larger part of the inlet stroke, and an atomized mixture of air and relatively heavy liquid hydrocarbon thereafter on the inlet stroke, compressing the mixture in the cylinder, igniting the compressed mixture, and allowing the ignited mixture to expand.

5. The method of obtaining power from an internal combustion engine which comprises sucking air into the cylinder for a larger part of the inlet stroke, and an atomized mixture of air and relatively heavy liquid hydrocarbon thereafter on the inlet

stroke, compressing the mixture in the cylinder, igniting the compressed mixture, and allowing the ignited mixture to expand.

6. The method of obtaining power from 5 an internal combustion engine which comprises sucking air of normal temperature into the cylinder for a larger part of the inlet stroke, and an atomized mixture of air and relatively heavy liquid hydrocarbon of 10 normal temperature thereafter on the inlet stroke, compressing the mixture in the cylinder, igniting the compressed mixture, and allowing the ignited mixture to expand.

7. The method of obtaining power from 15 an internal combustion engine which comprises sucking air of normal temperature into the cylinder for substantially three-quarters part of the inlet stroke, and an atomized mixture of air and relatively heavy 20 liquid hydrocarbon of normal temperature thereafter on the inlet stroke, compressing the mixture in the cylinder, igniting the compressed mixture, and allowing the ignited mixture to expand.

25 8. In an internal combustion engine, in combination, a relatively movable cylinder and piston, a carbureter adapted to contain relatively heavy liquid hydrocarbon, an air inlet for said cylinder, a valve governing 30 said air inlet, means adapted to open said valve and maintain it open for a larger part of the inlet stroke of the engine, and means adapted to permit fuel from the carbureter to be introduced into the cylinder in an 35 atomized condition after said larger part of the inlet stroke.

9. In an internal combustion engine, in combination, a relatively movable cylinder and piston, a carbureter adapted to contain 40 relatively heavy liquid hydrocarbon, an air inlet for said cylinder, a valve controlling said inlet, said carbureter being so connected with said cylinder that carbureted air will be drawn into the cylinder by a relative movement of said cylinder and piston at a greater rate than air through said inlet, means adapted to positively open said valve at substantially the beginning of the inlet stroke, and means adapted to close said 45 valve shortly prior to the end of said inlet stroke.

50 10. In an internal combustion engine, in combination, a relatively movable cylinder

and piston, a carbureter adapted to contain relatively heavy liquid hydrocarbon, an air 55 inlet for said cylinder, a valve controlling said inlet, said carbureter being so connected with said cylinder that carbureted air will be drawn into the cylinder by a relative movement of said cylinder and piston at a 60 greater rate than air through said inlet, means adapted to positively open said valve at substantially the beginning of the inlet stroke, means adapted to close said valve shortly prior to the end of said inlet stroke, 65 and a second valve adapted to prevent the retrogression of fluid from said cylinder to said carbureter as the engine operates.

11. In an internal combustion engine, in combination, a relatively movable cylinder 70 and piston, a carbureter adapted to contain relatively heavy liquid hydrocarbon, an air inlet for said cylinder, a valve governing said air inlet, means timed to operate said valve so as to cause said cylinder to be 75 filled with air at a predetermined point in the suction stroke prior to the completion of said stroke, and means whereby atomized fuel may pass into the cylinder from said carbureter prior to the completion of said 80 suction stroke but not until after said predetermined point in the suction stroke has been reached.

12. In an internal combustion engine, in combination, a relatively movable cylinder 85 and piston, an air inlet disposed to supply air to said cylinder, a valve adapted to govern said inlet, a carbureter connected for supply of relatively heavy liquid fuel to said cylinder, a check valve in the passage 90 between the cylinder and said carbureter adapted to open under suction in the cylinder, the valve of the air inlet being of greater area than that of the other valve, means adapted to positively open said air 95 inlet valve at substantially the beginning of the inlet stroke, and means adapted to close said air inlet valve prior to the end of said stroke.

In testimony whereof we affix our signatures in the presence of two witnesses.

CHARLES L. SNYDER.
FRED J. PEASE.
